UNITED STATES PATENT OFFICE

STEN WADSTEN, OF BLOOMFIELD, NEW JERSEY, ASSIGNOR TO WESTINGHOUSE LAMP COMPANY, A CORPORATION OF PENNSYLVANIA

ADJUSTABLE HOLDER FOR COIL-WINDING DIES

Application filed December 27, 1927. Serial No. 242,715.

The present invention relates to an improvement in coil-winding machines such as shown and described in the patent to J. W. Ekstedt, 1,670,499 granted May 22, 1928 and 5 assigned to the same assignee as is the present application.

In the above mentioned patent, a machine is shown for coiling fine hair-like wire to helical form in the absence of a mandrel and particularly for the production of such coiled wire to serve as filaments for incandescent electric lamps. The machine shown comprises mechanism for moving a wire through a given path when tangentially engaged by 15 a pair of oppositely disposed driving rollers which drive the wire endwise into a cavity die from which the wire issues in the form of a continuous helix. Means are also provided for cutting the helix into sections of proper 20 lengths to constitute filaments for incandescent electric lamps.

The die is so arranged that the cavity is positioned to receive the wire from the driving rollers, the bottom of the cavity being inclined or grooved so that the wire is bent into a succession of coils which pass over a lip or separator member at the edge of the die. The helix or successive turns of the coil which issue from the die are consequently spaced 30 a given distance apart, and a helix is, therefore, provided of a certain diameter and pitch depending upon the dimensions of the spacer member and the radius of curvature of the effective surface of the cavity as well as the 35 position of the die with respect to the driving rollers.

In the manufacture of coiled filamentary bodies which serve as electrical resistance elements when used as lamp filaments, it is essential to exercise extreme accuracy in the formation of the coils, since each filament or coiled section must be made in accordance with specified dimensions so that each coiled section will have a length of wire therein 40 equal to the succeeding coiled section. Furthermore, the diameter of the coil as well as the spacing or pitch of the turns of the coil 45 must be uniform.

The dimensions of the diameter and the 50 proportions of the coiled sections vary for

lamps of different wattage, and the data relating to such dimensions and proportions are known as the "rating" so that a coiled section for a given rating must be made in accordance with a predetermined set of dimensions. For example, a filament for a 60 watt, 115 volt lamp must contain a length of wire of 517 mm., it must have a coil diameter of .0108 inches and the coiled section must contain 398 turns per inch. The diameter of the wire also varies in filaments of different wattage lamps and the diameter of the wire of a coiled filament for a 60 watt lamp is preferably .00187 inches.

It will be obvious that in order to produce a lamp filament and hold the coil formation to the required proportions and dimensions it is necessary to accurately form the coil-winding die and to provide accurately adjustable means for holding the said die in a given relation to the path of movement of the wire thereto. In the above-mentioned patent, a coil winding die is shown and described as preferably consisting of an extremely hard material such as a diamond. A diamond die, although 65 having indefinite life, is difficult to produce, and owing to variations in the properties of a diamond, it is very often brittle to the extent that portions of the coil-winding lip are 70 broken off rendering the die inoperative for 75 the purpose intended.

As set forth in the said patent, the coil-winding die may be constructed from hardened steel, but inasmuch as the wire passing 80 over the die results in excessive wear, it is necessary to replace the steel die at shorter intervals than is necessary with a diamond die. Ordinarily the replacement of one die for another would offer a considerable disadvantage since when applying a die into position for the winding of a coiled filament it is necessary to adjust the die in several planes until the cavity is accurately located in such 85 position that the diameter and pitch of the coil produced will be in accordance with the data supplied for the rating of the particular lamp for which the filament is to be used.

When using a diamond die, the die remains 90 in the machine for such a long period that the amount of labor and inconvenience involved 95 100

in a change from one die to another is negligible. A steel die, although easier to produce, must be changed at comparatively short intervals, and the advantage given by the facility accompanying the production of the die is lost by the time and labor involved in replacing the same.

An object of the invention is to provide a means for forming a die adapted to cooperate with means for holding a die in a given coil-winding position.

Another object of the invention is to provide a die having a coil-winding cavity disposed in a predetermined relation to the axis 15 of the die.

Other objects and advantages of the invention will be more fully understood from the following description.

In practicing the present invention, I first 20 employ what may be termed a master steel female die blank and in one end thereof, a cavity is formed by means of any suitable high-speed rotary lapping wheel of the proper size. This master steel female blank is 25 then hardened and drawn to proper temper and used as a female die or hob for the production of the master male die.

In order to produce the master male die, the female hob is held in position and a rod 30 of unhardened steel, constituting the master male die blank, is pressed against the cavity, until metal from the blank fills the cavity, thus forming an extension or matrix which constitutes the master male die. The extension is obviously equal in dimensions to the cavity of the female hob. The master male die being thus produced may then be hardened and tempered. An unhardened die blank or rod may then be forced against the end of the 35 master male die until the die blank takes a depression or cavity from the master male die, thus the coil-winding cavity is formed in the die blank and a coil-winding die is produced which may then be hardened for use in a coil-winding machine.

The method of forming the cavity in the die blank is, however, utilized to make it possible to always produce the cavity in proper position for a coil-winding operation. This 40 is accomplished by providing means for locating a point or spot upon the die rod and in providing means in a holder of the coil-winding machine for engaging the said point or spot so that each die rod will be held in the 45 coil-winding machine in a position as determined during the formation of the cavity. By reason of this method, the first coil-winding die produced may be inserted into the die holder of a machine and secured in the pre-determined position. The die holder may 50 then be adjusted until the die is so positioned as to produce a helix of the proper pitch and diameter. The coil-winding operation may then be continued until it is necessary to substitute a new die.

Inasmuch as the next die produced is provided with a point or predetermined spot to be engaged by means in the holder of the coil-winding machine, the said die will take 70 exactly the same position as was occupied by the previously used die. This method makes it possible to not only quickly and conveniently produce a coil-winding die, but cooperates with the coil-winding mechanism 75 to such extent that a plurality of successive dies may be produced without further adjustment of the coil-winding mechanism to produce a helically wound wire of predetermined dimensions.

The invention will be more fully understood by reference to the accompanying drawings in which:

Fig. 1 shows a portion of a female hob for producing a master male die;

Fig. 2 is an end view of the hob shown in Fig. 1;

Fig. 3 is a fixture employed for forcing a master male blank against the hob to produce the master male die, and also for forcing the master male die against the die blank to produce the coil-winding die;

Fig. 4 is a side elevational view of the master male die;

Fig. 5 is an end view of the die shown in Fig. 4;

Fig. 6 is a cross-sectional view of a portion of the fixture shown in Fig. 3;

Fig. 7 shows a die in the form of a rod having the die cavity properly disposed at 100 one end thereof;

Fig. 8 is an end view of the die shown in Fig. 7;

Fig. 9 is a fragmentary perspective view of a coil-winding machine and shows a die 105 holder as employed for supporting the die;

Fig. 10 is a detailed view of the die holder partly in section;

Fig. 11 is a view of one end of the die holder shown in Fig. 10; and

Fig. 12 is a view of the opposite end of the die holder shown in Fig. 10.

In practicing the present invention, a hob 10 may be provided of any suitable material, preferably of steel which may be hardened 110 and tempered to the proper degree. The hob may be provided with a tapered end 11 terminating in a surface 12 and any suitable high-speed rotary lapping wheel 13 may be employed to produce a slot 14 in the surface 12. The lapping wheel 13 may be of such dimension as to produce the cavity 14 of the proper depth, length and width.

The female hob thus produced, may be hardened to serve for the making of a male 125 hob or matrix 15. This is accomplished by providing a fixture 16 comprising a member 17 formed to provide abutments or extensions 18 and 19. The extension 19 may have a force screw 20 passing through a threaded aperture, and a retainer member 21 may be

provided to receive ends of the hob 10 and a rod 22 from which the male hob is to be produced. The retainer member 21 may have a flattened lower portion 23 for disposition on a surface 24 between the extensions 18 and 19 and guide members 25 may be provided to hold the retainer member from lateral movement. When the rod 22 and the female hob 10 are disposed in the retainer member, the set force screw 20 may be actuated to thrust the ends of the said hob and rod together, thus causing the metal of the rod 22 to flow into the cavity in the female hob, thereby producing a projection 26 which has the same dimensions as the interior wall of the cavity in the female hob. The male hob thus produced may then be hardened and used to produce a coil-winding cavity 27 in a die rod 28 in the same manner as described for producing the male hob.

For the purpose of obtaining an accurate position of the cavity in each die rod produced, the die rods as well as the hob are provided with flattened portions 29 and 30 respectively, and set-screws 31 and 32 are provided to engage the flattened portions and thus hold the die rod and hob in proper relation during the formation of the cavity. The set-screws do not, however, hold the hob and die rod against longitudinal movement for the formation of the cavity.

Furthermore, the die blank is provided with a four-sided taper as shown in Figs. 7 and 8 and the cavity 27 is so disposed as to be adjacent to one side of the end of the rod, thereby permitting the edge 27' of the cavity to serve as a coil separating lip. It is obvious that if desirable, the cavity may be formed in any position on the end of the blank and the side of the blank ground down to provide a coil separating lip. By means of the present method, the cavity may be made in exactly the same position on each die produced.

In addition to the operation of forming the cavity in the die rod, the retainer member 21 of the fixture 16 is provided with an aperture 33 so that after the cavity has been formed in the die rod the hob and die rod may remain in fixed relation and a drill or other tool may be inserted through the aperture 33 to spot the die rod, forming a depression 34 to receive the end of a set-screw when the die rod is placed in a holder of a coil-winding machine, thus making it possible to accurately position each die rod in a manner to be presently described.

The coil-winding mechanism selected for use in connection with the above described apparatus is substantially the same as that disclosed in the above-mentioned patent, only such portion of the mechanism being shown as to clearly illustrate the present invention. As shown in Fig. 9 the coil-winding mechanism may comprise a pair of wire-driving

rollers 35 and 36, the roller 35 being mounted in an oscillatory bearing 37 pivoted at 38. The said roller 35 is provided with a shaft extending through a bearing 39. When the roller 35 is disposed in operative relation to the roller 36, both rollers frictionally engage a wire 40 and the shaft of the roller 35 is so arranged as to be connected with mechanism for rotating the roller. The bottom roller 36 is provided with a shaft to effect its rotation. The rollers may be driven from any suitable source (not shown) to cause a movement of the wire 40 for a coil-winding operation.

The above-mentioned patent fully illustrates mechanism for performing a coil-winding operation and also discloses a holder for a die. The present invention, however, includes an improved form of holder 41 which operates in conjunction with the die-forming operation for replacement of one die for another and to locate each substitute die in exactly the same position as that occupied by the previous die.

This holder comprises a casing 42 hinged at 43 to a spindle 44, the said spindle being disposed in a bearing 45' provided on the body of the coil-winding machine. By reason of the pivot 43 and the spindle 44, it is possible to move the casing 42 in a vertical and horizontal plane so as to adjust the die with relation to the wire driving rollers. Inasmuch as the die 28 is supported by the holder, an adjustment of the latter causes an adjustment of the die.

It is essential, however, to provide a more accurate adjustment of the die, and for this purpose a sleeve 45 is fitted to a suitable bore 46 in the casing. The sleeve 45 is provided with a longitudinal passage 47 to receive the die or die rod 28 and may be termed a die sleeve or collar. A set-screw 48 is provided to engage the notch or depression 34 in the die rod to hold the same in a predetermined relation to the sleeve. An adjustment of the die rod about its longitudinal axis may be obtained by a rotary movement of the sleeve 45.

For this purpose, the sleeve is provided with a yoke 49 having a split head 50 and a clamping screw 51 may be provided to secure the yoke to the sleeve 45. Arms 52 and 53 of the yoke extend downwardly and are positioned on opposite sides of a control arm 54 integral with the casing 42 of the holder 41. Set-screws 55 and 56 passing through threaded apertures in the arms serve to permit an adjustment of the yoke with a consequent adjustment of the sleeve 45 and die rod 28. A further adjustment of the die rod is accomplished by providing a set-screw 57 which extends through a threaded aperture in the yoke 49 and abuts against the casing 42. Thus by a manipulation of the set-screw 57, the sleeve and consequently the die may be moved toward or away from the wire driving rollers 35 and 36. For the purpose of clamp-

ing the sleeve in its final position, the casing 42 is split at 58 and a clamping screw 59 is provided.

By reason of the above-mentioned adjustment elements, the position of the holder 41 may be changed with a fine degree of accuracy and the die may be adjusted with relation to the holder.

The holder 41 as a whole may be adjusted vertically and horizontally by means of a control arm 54, an end 60 of which is disposed in a housing 61 which housing constitutes part of a slidable member 62 movable upon an arcuate plate 63, the said plate being secured to or integral with the body of the machine. A movement of the slide member 62 along the plate serves to accomplish a preliminary adjustment of the holder 41 and the said slide member may be screwed in position by set-screw 64. For the purpose of adjusting the control arm to regulate the position of the holder 41, set-screws 65, 66, 67 and 68 are provided. Set-screws 65 and 66 engage with the end 60 of the control arm to raise or lift the control arm and adjust the holder 41 vertically about the pivot 43. The set-screws 67 and 68 engage with opposite sides of the end 60 of the control arm 54 to adjust the holder 41 laterally or in a horizontal plane, which adjustment is possible by reason of the spindle 44 journaled in the bearing 45.

From the foregoing, it will be evident that coil-winding dies may be produced in a simple and accurate manner by first making the male hob 15. As shown in Fig. 6, when the die rod is in position and an aperture has been formed in the end of the die rod 28 by reason of the hob 15, the die rod may be spotted through the aperture 33. The distance between the end of the die rod and the center of the aperture 33 which is indicated by a letter X, may be of any selected dimension; having once been determined, however, this dimension is maintained. The die rod, after being spotted to produce the depression 34, is then applied to the sleeve 45 of the holder 41 and the set-screw 48 is screwed downwardly until the end of the screw enters the depression 34, thus determining the dimension between the center of the depression and the end of the die rod, which dimension is indicated in Fig. 10 by the letter Y.

After the die has been positioned in the holder, the holder is adjusted to proper relation with the driving rollers 35 and 36, and the wire is then forced into the die from which it issues in a series of successive coils to produce a helix.

The formation of the helix as above mentioned, must be extremely accurate as to pitch and diameter so that if a coil is to be made for use in a given watt lamp certain rating data are supplied and the coiled wire must be made to comply with the dimensions which are predetermined. In order to accomplish

this, it is not only necessary to provide a die with a spacing lip, but to so adjust the die with relation to the path of movement of the wire that the exact diameter of the helix will be obtained and the exact pitch or spacing between the successive coils will be obtained.

This operation is important and is clearly described in Patent Number 1,795,767 issued March 10, 1931, to John W. Ekstedt.

After the holder has been adjusted so that the die will lie in its proper relation to the wire-driving rollers and a coil of the proper proportions and dimensions is produced, the die may remain until such a number of coils have been produced as to cause a wear upon the die. A die may then be produced by the method as above described, and it is not necessary to make any further adjustments with respect to the holder but the new die may be applied to the holder and by reason of the predetermined spot or depression 34, the said die may be quickly and accurately positioned in exactly the right relation to the path of movement of the wire or the wire-driving rollers to produce a helix of exactly the same dimensions as produced by the die previously used.

A die produced by the present apparatus has the advantage of being more durable than one produced by merely cutting away the material to produce the cavity. It will be evident that by reason of the present device, the material which occupied the space of the cavity is forced away or compressed so that the surface or wall of the cavity is of greater density than the surrounding metal and more resistant to wear.

From the foregoing, it will be evident that the present apparatus makes it possible to utilize a coil-winding die which need only be of a material sufficiently hard to produce a reasonable number of lamp filaments, since owing to the present method, no material loss of time or inconvenience by the renewal of the die is encountered.

The present invention, therefore, eliminates the necessity of providing a die of a material such as a diamond which requires expensive labor by skilled workmen for its production as well as a relatively long time interval for its production. The present apparatus, reduces the cost of manufacture of fine coiled filamentary bodies by avoiding the use of an expensive tool subject to breakage, and furthermore, provides a machine, in which a die may be made and applied after the first installation without any special or usual skill on the part of an operator.

Although a preferred embodiment of the apparatus is shown and described herein, it is to be understood that modifications may be made therein without departing from the spirit and scope of the invention as set forth in the appended claims.

What is claimed is:

1. In a coil-winding machine including a die and wire-driving means for moving a wire into said die, the combination with a die holder, a sleeve for supporting a die, and means for adjusting said sleeve relative to said holder to position said die in a given relation to said wire driving means.
2. In a coil-winding machine including a die and wire-driving means for moving a wire into said die, the combination with a die holder, a sleeve for supporting a die, and means for reciprocating said sleeve along its longitudinal axis and for rotating said sleeve about said axis.
3. In a coil-winding machine including a die and wire-driving means for moving a wire into said die, the combination with a die holder, a sleeve for supporting a die, means for reciprocating said sleeve along its longitudinal axis, and means for rotating said sleeve about said axis and means for adjusting said holder.

In testimony whereof, I have hereunto subscribed my name this 22nd day of December, 1927.

STEN WADSTEN.
